TELEGRAPH PRINTER SYSTEM

William G. H. Finch, New York, N. Y.

Application April 28, 1933. Serial No. 668,390

16 Claims. (Cl. 178—4)

My invention relates to novel apparatus for and methods of automatic printing telegraphy and more particularly relates to novel methods of and apparatus for selecting, synchronizing and 5 operating portable and mobile automatic printing telegraph apparatus over radio.

Heretofore, due mainly to the complications of telegraph printers, they have been considered practical only for fixed station work.

10 A great need, however, has arisen for the operation of mobile telegraph printers; that is, printers which are mounted on movable carriers, such as automobiles, buses, trucks, police cars, aeroplanes, ships and the like.

15 Owners of these mobile printers are then supplied with a radio service for sending out recorded instructions. For example, the owner of a truck desiring to transmit instructions to the driver submits the message to the central station. The central broadcasting station operating on an assigned wave length then broadcasts the instructions which automatically are recorded on the printer mounted on a particular moving carrier.

20 25 The printer used must not only be rugged to withstand the unusual usage, but must be of simple construction having as few parts to get out of order as possible, operating on as simple a code as possible to avoid errors, and requiring only the simplest synchronizing.

Accordingly, I have as the main object of my invention the provision of a printing telegraph system operating a mobile printer by radio.

The operation of portable and mobile telegraph 30 printers by radio presents many problems which are not found in line operated telegraph printers. Accordingly many of the principles which have become standard with printing telegraph over lines such for example as standard synchronization cannot be applied to radio printing telegraphy. The usual start-stop synchronization principle per se in which the electrical interconnection of the transmitting and receiving apparatus is used to insure synchronization, cannot be applied to radio printing telegraphy.

35 The standard five-unit code in which impulse intervals of uniform duration are used to make the necessary selection of the high speed printer have not been as successful as desired. They 40 require complicated selecting mechanism and overlap devices. This has rendered these printers prohibitively costly and impractical for mobile use.

45 Accordingly an object of my invention is to provide a novel mobile, radio operated telegraph printer and novel methods for operating the same.

A further object of my invention is to provide 50 a novel code for automatic telegraph printers.

55 60 Still a further object of my invention is to

provide a two-unit code for directly operating a telegraph printer and substantially without the use of intermediary selecting apparatus.

Still a further object of my invention is to provide novel synchronizing means for telegraph 65 printers.

Another object of my invention is to provide an automatic telegraph printer in which synchronization is obtained in response to each impulse of the code.

Still a further object of my invention is to provide a telegraph printer, operated by a code comprising long and short impulses.

In the operation of printers, in a vehicle which is not only crowded for space but subjected to 70 much jarring, special mountings and arrangement of the printer is necessary.

Accordingly, a further object of my invention is to use novel mountings and supports for mobile printers.

Another object of my invention is to render the printer characters quickly and readily visible.

In operating telegraph printers by a radio it is of considerable importance, especially in the case of police signalling, that the code be kept secret so that unauthorized "listeners-in" will not be able to make any intelligence out of the message being sent.

To this end, complicated coding apparatus has been developed which is so involved that it is 90 costly and difficult to keep in practical operation.

Accordingly, a further object of my invention is to provide novel apparatus for and methods of maintaining the telegraph code secret.

A further object is to provide a telegraph 95 printer in which the characters can be readily interchanged to respond to different codes.

Still a further object is to provide type wheel printers in which the characters are responsive to different codes.

Still a further object of my invention is to 100 provide telegraph printers with removable and interchangeable type characters.

There are other objects of my invention which together with the foregoing will appear in connection with the detailed description to be given hereinafter.

In general, my invention contemplates a central station selling radio service to subscribers of mobile telegraph printers mounted on buses, 110 trucks, passenger cars and police cars. In the latter case particularly, the permanent record of the received message avoids any misunderstanding or loss of message by temporary absence from the car. It also insures a greater secrecy.

In accordance with my invention, land communications may also be conducted with ship and aeroplanes, between ships, between aeroplanes, and from ships and aeroplanes to land.

The telegraph printer of my invention com- 115 120

prises a plurality of disc-shaped type wheels secured together on a type wheel shaft. Each disc in turn carries a number of individual embossed characters to be printed.

5 This type wheel construction is directly, selectively operated by what I prefer to call a two-unit code, each unit consisting of a combination of long and short impulses. The long impulses of one unit selectively shift the type wheel shaft to select a type wheel disc and the long impulses of the second unit selectively rotates the type wheel shaft to select a character of the selected type wheel disc.

10 A distributor directly controlled by each unit counts the impulses for synchronizing and at the proper impulse, switches the oncoming signals in synchronism therewith to select the type wheel disc and then the character on the disc.

15 To insure secrecy of the code, I provide means to interchange the position of the characters.

20 The printer is mounted on the vehicle in a manner to prevent serious vibrations and therefore injury thereof.

25 Referring to the drawings:

25 Figure 1 is a diagrammatic view of the circuits and apparatus employed in one form of my invention.

30 Figure 2 is a side elevation of the distributor mechanism employed in Figure 1.

35 Figures 3 to 6, inclusive, are sections taken responsive on lines 3-3, 4-4, 5-5 and 6-6 of Figure 1.

35 Figure 7 is a perspective view of a form of type wheel disc showing particularly the arrangement of obtaining space between words.

40 Figure 8 is a developed diagram of a preferred form of type wheel construction.

40 Figure 9 is a fragmentary portion of one form of message transmitting tape which may be used in my invention.

45 Figure 10 is a sectional view of the printer mounted in an automobile.

50 Figure 11 is a front plan view of the dash board of the automobile.

55 Referring now more particularly to Figure 1, the system of communication diagrammatically illustrated therein consists generally of a code transmitting device 10, a receiving device 11, a receiver controlled relay 12 for repeating the received code combinations of impulses to the selecting and recording system, a controlling device 13 responsive to the short and long impulses of the received code and a printing mechanism which is selectively actuated to progressively print upon a movable tape 14 a letter or character corresponding to the transmitted code combination of short and long electrical impulses assigned to represent that character.

60 More specifically, the transmitting device 10, preferably a radio transmitter adapted to broadcast short and long electrical impulses, may be operated in any desired manner such as manually, photoelectrically, or mechanically. As illustrated in the drawings, a perforated tape 15, having therein groups of perforations comprising short slots or holes S and long slots L (see Figure 9), is fed through a scanning mechanism 16 associated with the transmitter 10. The scanning mechanism 16 responds to and translates the groups of perforations into radio electrical impulses which are broadcast through the antenna 17 in any well-known manner. The impulses may then be picked up by the antenna 18 of the tuned receiver 11 of any well-known construction and caused to energize the relay 12.

The code transmitted comprises a synchronizing impulse followed by a two-unit code combination.

In response to the synchronizing impulse, relay 12 which is an extra slow relay is energized.

10 Normally relay 12' whose winding is of a lower resistance than the series windings of magnet 48 and relay 100, provides a bypass circuit for the current from battery 111 over contact 23' and brush 20 to ground at 121. Relay 12', however, upon being energized over this circuit, opens the circuit at its armature 13' which disengages its back contact.

15 Thereafter upon receipt of the first signal impulse, the circuit completed extends over conductor 113 as will be explained hereinafter, since relay 12' being slow to release is not deenergized during the no-impulse period.

20 If, therefore, the synchronizing impulse is received while brush 20 is on contact 23', normal operations proceed as will be described.

25 If, on the other hand, no synchronizing impulse is received when brush 20 is on synchronizing contact 23', no operation can occur. For reasons that will appear hereinafter brush 20 will remain 100 on contact 23' until the synchronizing impulse showing that the transmitter and receiver are in synchronism is received.

30 The synchronizing impulse is much longer than even the long impulse of the code to be described 105 in order to energize extra slow relay 12'. As soon as relay 12' is energized, stepping magnet 48 is energized over a circuit to be described in connection with the code signals. Brush 20 is moved from contact 23'. At the end of the synchronizing impulse, magnet 48 is deenergized stepping the brush a further distance and the apparatus is ready for the first signalling impulse.

35 In response to the first signal impulse energizing relay 12, an energization circuit is completed 115 from the battery 111 front contact and armature 110 and conductor 113 through the magnet 48, conductor 114 and relay 100 to ground at 115.

40 Magnet 48 is a stepping magnet controlling the operation of the distributor device 13 which 120 controls the switching of the oncoming impulse to mechanisms, to be described, responsive to the two-unit code and controlling the final printing and restoration of the printer.

45 This switching is effected by the brush or contact arm 20 which is mounted on, and locked by a key to one end of a rotatable shaft 21, the other end of which carries a friction plate 22. Shaft 21 is driven by a motor 40 (Figure 2) through worm 41 mounted on a shaft of the 130 motor and meshing with a worm wheel 42 secured to and driving shaft 43. Secured to for rotation with shaft 43 is the friction disc 44 including plates 22 and 45.

50 As motor 40 rotates, shaft 21 carrying distributor arm 20, tends to rotate with it, but is normally prevented from rotating by the pawl 47 in engagement with one tooth of the ratchet 46, secured to the shaft 21. One end of the pawl 47 consists of an armature controlled by a magnet 48 to which the armature is attracted when that magnet is energized. Normally, however, the pawl 47 is held against its backstop as shown in Figure 1 by a spring 49, one end of which is secured to the pawl 47 and the other to the frame 145 work.

55 When magnet 48 is energized in the manner described above, it attracts pawl 47 which rocks about its pivot withdrawing the lower tooth of pawl 47 from the ratchet wheel 46 and moving its 150

upper tooth in the path of the ratchet wheel permitting a rotation of the shaft 21 with arm 20 through an angle equal to one-half the pitch of the teeth of ratchet wheel 46.

5 The distributor arm 20 is moved successively into engagement with a series of contacts 24 to 36 consisting of contacting points mounted on an insulating ring 13. Each of the contacts 24 to 28 is common to a character on each disc wheel, 10 five contacts being shown here for purposes of illustration of a printer in which there are five characters on each disc wheel to be described. Each of the contacts 29 to 34 is individual to a type wheel disc of a printer consisting of a plurality of such discs. Contact 35 controls a printing operation and contact 36 a restoring operation all of which will be described in more detail hereinafter. The pitch of the teeth of ratchet 46 is equal to the angular displacement between 15 successive contacts so that when magnet 48 is energized to permit the escapement mechanism 46 and 47 to operate, the distributor arm 20 is rotated either from a contact to a point intermediate the contact and a successive contact or from an intermediate point to a succeeding contact. With brush 20 therefore in the normal position shown, the receipt of the first code impulse energizing relay 12 which in turn energizes the escapement magnet 48 will permit rotation of 20 brush 20 in the direction of the arrow shown to the first contact 24. It will be recalled that the escapement magnet 48 was energized in a series circuit with the relay 100.

Relay 100 is a slow-to-energize relay constructed so that it will not respond to the short impulse of the code but is only responsive to the long impulse. If, however, the first impulse received is a long impulse, relay 100 will energize after an interval of time and an energizing circuit will 35 thereupon be completed from ground at 121 over distributor brush 20, contact 24, conductors 120 and 119, through the selector relay 79, conductors 118 and 117, front contact 101 and armature 102, conductors 116 and 112 and through battery 111 to ground. The effect of the energization of relay 79 will be described hereinafter.

Upon the completion of the first code impulse, relay 12 is deenergized, opening the energizing series circuit for the magnet 48 and relay 100. 50 Upon the deenergization of relay 48, pawl 47 is restored to the position shown permitting rotation of shaft 21 for a distance equal to half the pitch of the ratchet 46. Brush 20 rotates from contact 24 to a point intermediate contacts 24 and 25. Selecting relay 79 is deenergized and the apparatus is back in normal condition in preparation for the next impulse.

The same cycle of operations is now repeated, brush 20 moving into engagement with contacts 60 25 and 28 successively in response to each impulse received and in turn controlling the selective energization of relay 79 in accordance with whether the received impulse is long or short.

65 The first unit selection is completed when the brush 20 leaves contact 28 and the second unit selection begins when the brush engages contact 29. If a long impulse is received at this time, relay 100 is energized and a circuit is completed from ground at 121, brush 20, contact 29, conductor 132 and 131 through the magnet 70, conductor 130 and thereafter over conductor 117 to battery 111 and ground as described hereinbefore.

75 Relay 70 is a second selection relay which is

energized in response to long impulses in the second unit of the code for selecting the particular type wheel disc. Relay 79 having previously selected a particular column of characters, a final selection is thus completed as will be described in more detail hereinafter. The selection having been completed, the printer is now in position for operation and on receipt of the next impulse which is the printing impulse, brush 20 engages contact 35 to extend the energizing circuit from ground at 121 over conductor 134 to the printing magnet 90 and conductor 133 to battery 111 and ground. Upon the energization of the printing magnet, the printing operation of the selected character is completed. Brush 20 is now moved to contact 36 to complete an energizing circuit over conductor 137 for the restoring magnets 86 and 72 in series over conductors 135 and 137. Magnets 86 and 72 upon energization restore the apparatus to normal. Following the restoration of the apparatus, brush 20 moves to its normal position shown on synchronizing contact 23'. It will be noted that contact 23' is spaced one-half a tooth pitch from contact 36 and one and one-half of a tooth pitch from contact 24. At the 100 end of the last signal, relay 12 is deenergized to move brush 20 to contact 23'.

Upon receipt of the synchronizing impulse, relay 12 is energized to energize relay 12' if the impulse is long enough. Magnet 48 is energized 105 as soon as relay 12' energizes to move brush 20 off of contact 23'. Thereupon magnet 48 is deenergized at the end of the synchronizing impulse and brush 20 moves to one-half a pitch distance from contact 24 in preparation for the 110 first signalling impulse.

If during the signalling period, an impulse is lost and distributor brush 20 so falls out of synchronism with the transmitter brush 20 will continue to be stepped until it reaches synchronizing 115 contact 23'. It will then be held at this position because of the deenergized condition of relay 12' providing a bypass around magnet 48 until a synchronizing impulse energizes relay 12'. This insures distributor brush 20 always starting out 120 in synchronism.

The printer will now be described in more detail.

The printing mechanism consists of a vertical shaft 50 mounted in a frame so as to allow for 125 both rotary and axial reciprocation. Upon the upper end of the shaft are removably keyed a series of seven type-discs 1 to 7 inclusive. These type-discs have six faces each upon each of which characters such as the letters of the alphabet, 130 marks of punctuation, numerals, etc, are embossed. An inking roller 51 is in frictional engagement with the discs so that during the setting of the discs the characters will pick up the proper amount of ink to print the characters upon the 135 tape 14. It is understood that other methods of inking or printing may be employed, such as an inked ribbon placed between the type and the tape as in the typewriter.

The lower end of the shaft 50 is supplied with 140 an anti-friction ball 52 which rests upon the periphery of a disc selector cam 53 (Figure 5). The cam 53 is loosely mounted but held against longitudinal movement, midway upon a horizontally disposed shaft 54. One end of this shaft 54 145 (left in Figure 1) is journaled in a frame member and beyond which it carries a plate 55 which is in frictional engagement with a continuously running friction disc 56.

The disc 56 is continuously driven by a motor 150

57 through the worm 58 and worm wheel 59. A torsion spring 60 encircling the shaft 54 and having one end secured in the hub of the cam 53 and the other end in the frame serves to urge 5 the cam to its normal position of rest where the vertical shaft 50 is in its lowest position, as shown in Figure 5. This position of rest is determined by a stop pin 61 carried by the cam coming in contact with a stop lug 62 carried by a 10 frame member.

Slidably keyed upon the shaft 54 adjacent the cam 53 is a clutch member 65 cooperating through said teeth with a clutch member 66 formed on the side of the cam facing member 65. The number of teeth in the clutch members corresponds to the number of type-discs on the vertical shaft 50. This is seven in the form of mechanism illustrated. The clutch member 65 is normally held in engagement with the member 66 on the 20 cam by a compression spring 67.

The rotation of cam 53 is accomplished in a similar manner to the rotation of the arm 20 of the control mechanism. Shaft 54 is allowed to rotate with friction disc 56 only when the proper impulses operate an escapement mechanism. To effect this movement, there is formed upon the periphery of the clutch member 65, a seven tooth ratchet wheel 68 (Figure 6). In functional association therewith is an escapement mechanism consisting of a pawl 69 and electro-magnet 70. Upon the actuation of the magnet 70, the pawl 69 allows the shaft 54 to rotate a distance of one ratchet tooth and thus, through clutch 65, 66, rotate the cam 53 a sufficient amount to elevate the type-discs a distance equal to one of their thicknesses.

After the printing operation has taken place (to be described hereinafter) the resetting of the cam 53 is accomplished by disengaging the clutch 65, 66, whereby the spring 60, which was being wound up during the setting of the vertical shaft 50, serves to immediately return the cam to its original position. The means for disengaging the clutch 65, 66 consist of a forked lever 71, pivot upon the frame and co-acting with the grooved hub of clutch member 65, and electro-magnet 72 for actuating lever 71.

In addition to elevating the group of type-discs, the proper amount as described above, the 50 discs 6 are rotated so that the proper character on the disc opposite the printing mechanism is brought into position to be printed. Of course if the character to be printed is on the face already in position, no rotation is necessary. The mechanism whereby the disc shaft 50 is rotated comprises a ratchet wheel 75, which is slidably keyed upon the shaft 50 but held in longitudinal position by surrounding frame members, and a pull finger 76 (Figure 4) adapted to rotate the ratchet 55 75 a sixth of a revolution at each pull. Finger 76 is carried upon an extension 77 of the movable core 78 forming a part of the solenoid 79. Thus, upon the solenoid being energized by a message impulse, the core extension 77 and finger 60 76 serve to rotate the shaft 50 one sixth of a revolution.

In order to maintain the shaft 50 and type-discs 1 to 7 in accurate angular position after each movement, a pivoted spring detent 80 is 70 normally held in engagement with the back face of a tooth on the ratchet 75 in such a manner as to prevent backward movement of the ratchet but allowing forward movement of same.

As soon as the printing has taken place, it is 75 necessary that the type-discs be returned to both

their original or normal angular and vertical positions in readiness for the next cycle. To perform this operation there is provided a combined torsion and compression spring 81 which encircles an upwardly extending portion 82 of the shaft 50 and has one end secured in a frame member and the other end in a thrust collar 83 fixed on said shaft. Thus it will be seen that, as the type-disc shaft is elevated and rotated, the spring 82 is both wound up and compressed. Resetting of the shaft 50 vertically downward by means of spring 81 takes place as the clutch 65, 66 is disengaged and cam 53, under influence of spring 60, returns to its low position.

The rotational resetting of the shaft 50 is accomplished by withdrawing the spring detent 80 from contact with ratchet 75 whereby the spring 82 unwinds and returns shaft 50 to its original position as determined by a stop finger 84, which is slidably keyed on shaft 50, striking a lug 85 carried on a frame member. Spring detent 80 is withdrawn from its contact with ratchet 75 by means of electro-magnet 86 acting upon an armature 87 formed as the rear portion of the detent.

It is sometimes desirable in communication and particularly radio communication, to have a message in code form. Heretofore this has been accomplished in the mechanism by sending the original message in code form so that the printed representation is a copy of the transmitted message which was in code. According to my invention, I send the message in its decoded form but receive and print it from type-discs which have been displaced from their original positions. In the mechanism as illustrated, the rearranging of the type-discs is accomplished merely by disconnecting shaft extension 82 from shaft 50, to which it is removably attached by a squared socket formed in collar 83, and slipping the type-discs off the shaft and replacing them in any desired order. Thus in the printing of the message, instead of printing the character represented by the transmitted impulses, another character is printed which, in the code form, represents the original character.

After a code combination of message impulses representing a particular character have been translated into a corresponding set-up of the type-discs, it is necessary to record this set-up on a tape and move the tape so that the next recording may take place. This is accomplished by a hammer and tape feed mechanism placed adjacent the type discs and operated by an electro-magnet 90. The energizing of magnet 90 thus forces hammer 91 to strike tape 14 thus printing the set-up character thereupon. Associated with the hammer 91 and operated by the movement of same is a tape feed mechanism comprising a tape feed wheel 92' (Figure 3) mounted upon a shaft 93, a ratchet wheel 94 for rotating shaft 93 and a feed pawl 95 mounted upon the end of a pivoted feed lever 96 the opposite end of which is in contact with the rear face of the hammer 91. A spring 97 serves to cause feed lever 96 to follow the movements of the hammer 91. It will thus be seen that as the hammer moves forward to perform the printing operation the lever 96 rocks upon its pivot and draws the pawl 95 over a predetermined number of teeth of ratchet 94 to feed the tape. When the hammer 91 is returned to its original position by means of a spring 98 attached to the bell-crank 92, the feed lever 96 is rocked in the opposite direction and causes the

tape 14 to be fed forward a distance sufficient to permit printing of the next character.

Referring now to Figure 8, there is shown a diagram of one system of type-disc markings and disc arrangement wherein the horizontal rows 1 to 7 inclusive represent the several type-discs and the vertical rows *a* to *f* inclusive represent the aligned faces of the type-discs. As shown in Figure 1, the normal setting of the mechanism has disc 1 and the character M in the printing position. This character M thus may be printed without further setting of the machine, but any other character requires the various settings previously described. A space between words is produced in the same manner as a printed character but no printing takes place because the disc face corresponding to the space impulses is cut away. (See Figure 7.)

The operation of the system of short and long electrical impulses required to run the mechanism through a cycle consisting of radial type-disc set-up, vertical set-up, printing, tape feed and return of parts to original positions should now be apparent. Fourteen impulses are required to rotate the control arm 20 through one revolution. The first five impulses serve to align radially the proper disc face with the printing mechanism. This is accomplished by successive contacts of arm 20 with contact point 24 to 28 inclusive and the action of the slow-to-energize relay 100. The latter is connected in series with the arm escapement magnet 48 and operates only in response to the long impulses. The next six impulses control the vertical alignment of the type-discs through the action of arm 20, contact points 29 to 34 inclusive, cam escapement magnet 70 and slow-to-energize relay 100. The twelfth impulse operates the printing magnet 90 to print the set-up character and then move the tape to the next position. The thirteenth and fourteen impulses are utilized for connecting the arm 20 with contact plate 36 to energize type-disc restoring magnets 72 and 86. Two impulses are used for the last operation to insure an elapse of time sufficient for the restoring operation although if desired only one impulse may obviously be used.

The short and long impulses are used, in conjunction with the slow-to-energize relay 100, to properly align the type-discs in the following manner: The short impulses do not operate the slow-to-energize relay 100 and hence cause no movement of the shaft 50; the long impulses energize the slow-to-energize relay 100 sufficient to close its contact 101 and armature 102 and thus in turn energize either solenoid 79 or cam release magnet 70. Thus, in the series of fourteen impulses representing, for example, the character "C", the first five would consist of four long and one short impulses, which would operate solenoid 79 four times and rotate type-disc from column *c*, Figure 8, to columns *d*, *e*, *f*, and *a* successively and thereby align the face of disc 3 carrying the character C, with the printing mechanism. Of the next six impulses the first two would be long and the following four, short. This would cause magnet 70 to allow cam 53 to move twice and elevate shaft 50 to bring the type disc 3 and character C thereon opposite the printing mechanism. The succeeding three impulses serve to print the character C and return the parts to original position as previously described.

Referring to Figure 9 there is shown one form 75 of tape 15 for transmitting messages to be re-

ceived on the herein disclosed mechanism wherein the long synchronism and fourteen short and long perforations representing the character C are distributed as follows (reading from right to left): a long synchronizing slot, four long slots, one short, two long, five short, one long. These slots may be arranged consecutively on the tape in any desired manner. When the tape is fed through the scanning device 16 of the transmitter 10 there is broadcast a similar group of electrical impulses which may be picked up in the manner already described.

In Figures 10 and 11 I have shown one preferred manner of mounting the printer on the radio set in a vehicle for mobile use.

As shown, the radio receiving circuit is mounted in a metal container 144 for protecting it from outside disturbances, particularly such as are found in a moving vehicle. Container 144 is mounted through a spring cushioning device 145 on the brackets 146 secured to the lower edge of the dash board 140.

Mounted just above the radio set is a frame construction 153 having spring cushioning supports 154. Electrical conductors 151 and 152 extend from the radio set to the relay 12, mounted in frame 153 which also carries the remaining parts of the printing mechanism which is shown with portions cut away.

As the characters are printed on the tape 14, 105 the tape is fed inwardly in the arrangement shown in Figure 10 so that the characters sweep from right to left along the lens 156 mounted by means of the supports 157 on the bracket 158. The simple amplifying arrangement is provided 110 by lens 156 for projecting the characters through a slot at 142 caught in the dash board and through which the characters are made visible to the driver sitting in the car opposite the dash board. The arrangement is such that the character is 115 projected and made visible instantaneously so that the driver is apprised of the message as soon as it has been received.

After the tape has been fed past the tape 142, it falls into the basket 161 mounted on basket 162. 120 The driver may at any time read portions of the message which have dropped into the basket by swinging the closure 143 on its pivots to a horizontal position and reaching into the basket. The basket as shown is located on one side of the 125 printer where it is easily accessible.

It will be understood that I have disclosed only one form of printing and that any other supporting means may be used for my mobile printer. Furthermore, although I have shown 130 the printer mounted in an automobile, it will be obvious that it may be mounted in any other movable object such as aeroplanes, ships, and so forth.

It will be obvious to those skilled in the art, 135 that my printer may take other forms than that herein shown, which is merely described here in detail for purposes of illustrating the principle of my invention, and I do not intend to be limited thereby except as set forth in the appended 140 claims.

I claim:

1. In a signalling system, a transmitter, a receiver, a single signalling channel connecting said transmitter and receiver, a telegraph typewheel 145 printer comprising a plurality of typewheel discs responsive to received code combinations of impulse conditions all of the same polarity received over said signalling channel, and means for directly operating said printer first to select a 150

typewheel disc and then a character on the type-wheel disc.

2. In a signalling system, a transmitter, a receiver, a single signalling channel connecting said transmitter and receiver, a telegraph typewheel printer comprising the type characters of the alphabet, a pair of electromagnets responsive to received code combinations of impulse conditions over said signalling channel for selecting the type characters for printing, switching means for switching predetermined ones of said impulses to one of said magnets and other predetermined impulses to the other of said magnets and synchronizing means for controlling said switching mechanism operation in timed relation with said received signals.

3. In a signalling system, a transmitter, a receiver, a single signalling channel connecting said transmitter and receiver, a telegraph printer comprising a type wheel shaft; a plurality of type discs secured thereto; means responsive to received code combinations of impulse conditions over said channel for selectively controlling the rotation of said type wheel shaft and moving it along its axis to select a type disc and a character on the selected type disc for printing and means for synchronizing said first means and said received impulses.

4. In a signalling system, a transmitter, a receiver, a single signalling channel connecting said transmitter and receiver, a telegraph typewheel printer comprising a type wheel shaft; a plurality of type discs secured thereto; means comprising solely a pair of magnets responsive to received code combinations of impulse conditions over said channel for selectively controlling the rotation of said type wheel shaft and moving it along its axis to select a type disc and a character on the selected type disc for printing, switching means for applying predetermined ones of said impulses to one of said pair of magnets and other of said impulses to the other of said magnets and means for synchronizing said switching means and received impulses.

5. In a signalling system, a transmitter, a receiver, a single signalling channel connecting said transmitter and receiver, a telegraph typewheel printer comprising a type wheel shaft; a plurality of type discs secured thereto; means for rotating said type wheel shaft and moving it along its axis and selector mechanism responsive to received code combinations of impulse conditions for selectively controlling said rotating means to select a type disc and a character on the selected type disc for printing; and a switch for switching predetermined impulses of the received code combination from one to the other of a second pair of magnets.

6. In a signalling system, a transmitter, a receiver, means for transmitting code combinations of impulse conditions to said receiver, said receiver comprising a printer including removable individual character discs, said discs being interchangeable whereby said printer is responsive to secret codes.

7. A telegraph printer comprising a type wheel consisting of a plurality of independent discs, each carrying a plurality of characters and means responsive to a two-unit code of long and short impulse conditions, one unit for selecting the type disc and one for selecting the character on the type disc.

8. In combination, a printer, a distributor for distributing received long and short impulses to selectively operate said printer, said distributor

means counting said received impulses and means cooperating with said distributor for normally preventing the operation of said printer except when it is in synchronism with said impulses.

9. In a telegraph printer; a magnet responsive to received code combinations of impulse conditions each code combination consisting of a plurality of groups of code impulse conditions; selector mechanism therefor comprising a plurality of relays; switching means for applying each group of said received impulse conditions to its associated relays; and synchronizing means for controlling the operation of said switching means in synchronous relation with said received impulse condition whereby invariably predetermined ones of said impulse conditions are applied to associated selector relays.

10. In a telegraph printer; a magnet responsive to received code combinations of impulse conditions, each code combination consisting of a plurality of groups of code impulse conditions; selector mechanism therefor comprising a pair of relays; switching means, said switching means comprising a distributor and rotating brush for applying each group of said received impulse conditions to its associated relays; and synchronizing means for controlling the operation of said switching means in synchronous relation with said received impulse condition whereby invariably predetermined ones of said impulse conditions are applied to associated selector relays.

11. In a telegraph printer; a magnet responsive to received code combinations of impulse conditions, each code combination consisting of a plurality of groups of code impulse conditions comprising a selector mechanism consisting of a pair of relays; a distributor comprising a plurality of contacts individual to each of said relays; circuit connections from said receiver and through said distributor whereby a plurality of predetermined impulses of each received code combination are applied through their individual contacts on said distributor to the associated relays; and means whereby said relays are responsive to said plurality of said impulse conditions to selectively operate said printer.

12. In a telegraph printer; a type wheel, a type shaft carrying said type wheel; motor means normally tending to rotate said type shaft; electromagnetic means selectively operative to received code combination of impulse conditions for releasing said motor power to rotate said type shaft step by step; a second source of power normally tending to move said type wheel shaft longitudinally; and electromagnetic means responsive to received combination of impulse conditions for selectively releasing said power to permit said shaft to be moved longitudinally.

13. In a telegraph printer; a type wheel; a type shaft carrying said type wheel; motor means normally tending to rotate said type shaft; electromagnetic means selectively operative to a received code combination of impulse conditions for releasing said motor power to rotate said type shaft step by step; a second source of power normally tending to move said type wheel shaft longitudinally; and electromagnetic means responsive to a received combination of impulse conditions for selectively releasing said power to permit said shaft to be moved longitudinally; and a distributor for selectively applying said received impulse conditions to said electromagnetic means.

14. In a telegraph printer; a type wheel; a type shaft carrying said type wheel; motor means

- normally tending to rotate said type shaft; electromagnetic means selectively operative to received code combination of impulse conditions for releasing said motor power to rotate said type shaft step by step; a second source of power normally tending to move said type wheel shaft longitudinally; electromagnetic means responsive to received combination of impulse conditions for selectively releasing said power to permit said shaft to be moved longitudinally; and a distributor for selectively applying a plurality of received impulse conditions to each of said electromagnetic means.
15. In a telegraph printer; a type wheel; a type shaft carrying said type wheel; motor means normally tending to rotate said type shaft; electromagnetic means selectively operative to a received code combination of impulse conditions for releasing said motor power to rotate said type shaft step by step; a second source of power normally tending to move said type wheel shaft longitudinally; electromagnetic means responsive to a received combination of impulse conditions for selectively releasing said power to permit said shaft to be moved longitudinally; a distributor comprising a plurality of contacts individual to each of said electromagnetic means restoring electromagnetic means and a printer magnet, said distributor having individual contacts for said restoring electromagnetic means and said printer magnet; circuit means whereby said distributor applies predetermined ones of said received impulse conditions to each of said selector magnetic means; circuit means following said operation of said selector magnetic means for applying an impulse condition to said printer magnet from said distributor; and circuit means including said distributor for energizing said restoring electromagnetic means following said printer operation whereby said type wheel is restored to normal.
